(57) **CLAIM**

The ornamental design for a battery charger for earphones as shown and described.

DESCRIPTION

FIG. 1 is a front perspective view of a battery charger for earphones, showing our new design in a closed position; FIG. 2 is a rear perspective view thereof; FIG. 3 is a front elevational view thereof; FIG. 4 is a rear elevational view thereof; FIG. 5 is a top plan view thereof; FIG. 6 is a bottom plan view thereof; FIG. 7 is a right-side elevational view thereof; FIG. 8 is a left-side elevational view thereof; FIG. 9 is a front perspective view showing the battery charger for earphones of FIG. 1, shown in an open position; FIG. 10 is a front elevational view thereof; FIG. 11 is a rear elevational view thereof; FIG. 12 is a top plan view thereof; FIG. 13 is a bottom plan view thereof; FIG. 14 is a right-side elevational thereof; and, FIG. 15 is a left-side elevational view thereof.

The broken lines shown in the figures depict portions of the battery charger for earphones that form no part of the claimed design.
